WILLIAM WINGARD AND LEONARD VERHULST, OF ST. PAUL, MINNESOTA

LOCKING DEVICE FOR MILK-CAN COVERS

Application filed January 4, 1928. Serial No. 244,433.

Our invention relates to covers of the kind used on milk and cream cans in the dairying industries, and the main object is to provide a simple, efficient and inexpensive locking device the use of which eliminates the possibility of can covers coming off during transportation of the cans. Further objects and advantages will appear in the following specification, reference being had to the accompanying drawing, in which,—

10 Fig. 1 is a top view of a preferred type of our improved can cover.

Fig. 2 is an approximately vertical diametrical sectional elevation about as on line 2—2 in Fig. 1.

15 Fig. 3 is a diametrical section about at right angles to sectional elevation Fig. 2 and about as on line 3—3 in Fig. 1, showing also in section the upper part of a milk can in which the cover is shown in locked position.

20 Fig. 4 is an enlarged sectional view of the center part of our improved can cover about as on line 4—4 in Fig. 2.

Fig. 5 is a modification of Fig. 2 and including partly in section the upper portion of a milk or cream can of the usual type.

25 Referring to the drawing by reference numerals 5 designates the upwardly tapering or shoulder part of a milk can above which is the usual vertical neck or collar part 5N and atop of the latter the integral upwardly flared mouth 5F the upper perimeter of which is formed with a bead 5B.

Our improved can cover is in general appearance the same as the usual well known type having a cup like lower part 6C of a size to fit snugly within the neck 5N of the can and formed concentric above said part 6C is the usual upwardly flared integral part 6F simultaneously fitting snugly within the part 5F of the can as shown. 6T is a perimetral top part or rim formed at its edge with a bead 6B normally concentric of and outwardly of the bead 5B when the cover is on the can.

30 In Figs. 1, 2, 3, and 4, 7 designates the usual type of channel shaped cover handle arranged diametrically in the cover and with its ends suitably fixed as at 8 on the diametrically opposite inner faces of the funnel like part 6F. In our device the center part of the

35 web of said handle may be offset upwardly as at 7A in Figs. 2 and 3 and 9 is an auxiliary lower web or strap parallel to and below part 7A and fixed to the under side of the handle as at 10. 16 is a vertical shaft pivoted in the center of parts 7A and 9 and carrying two eccentric cam discs 12 and 13 of which 12 is the upper one and 13 the lower one. 14 is an eccentric strap about each cam 12—13 and from each said strap extends a 40 bar 14B, said bars extending outwardly radially and slideable each through an aperture 15 of a suitable bearing 15B preferably formed of the metal in skirt part 6F of the cover as in Figs. 1 and 3. The eccentricities 12—13 are fixed on shaft 16 so that the throw or eccentricity of one is diametrically opposite the other, thus providing for corresponding simultaneous inward or outward movement of the bars 14—13, respectively in or 45 out of engagement with diametrically opposite apertures 17 in the flared parts of 5F of a can.

50 The said diametral movement of bars 14B is of course accomplished only by rotating shaft 16, for which purpose a horizontal handle 18 is provided and pivoted on top part of shaft or pin 16, and the outer extremities of said bars and size of cams 12—13 must be calculated to be such that said extremities are 55 drawn inwardly out of engagement with the apertures 17 in the can but each always engaged within the aperture 15 of the cover. When the cams are swung so that the extremities of bars 14B project through the apertures 17 of the can it is obvious that the cover is securely locked in closing position of the can opening. In this locked position handle 18 is preferably longitudinally above the handle 7 and its end is frictionally engaged 60 with a leaf spring locking member 19 fixed at 20 on the handle, as in Figs. 1 and 2, the said handle being simply released by pressing the spring leaf away from contact as indicated by dotted lines 19X, Fig. 2.

65 In the modification, Fig. 5, the handle 7 is tubular and the eccentric operated means are entirely enclosed in the handle and operating of course longitudinally therein instead of at right angles to the handle as in Figs. 1 70

to 4 inclusive. In this modified construction handle 18 is on top of the handle and near its free end provided with a depression 18D adapted to engage an upward projection 7P in the top part of the handle when the device is in locked position.

In the use of our device it is clear that the can cover is used in the same manner as all ordinary can covers, but before putting our cover in place on a can the lever 18 is swung to a position contracting the bars 14 and the cover is put in place so that said bars will subsequently be engaged slidably in the apertures 17 of the can when the handle 18 is turned to locking position, that is, when the bars 14B have been projected outwardly to engage in said apertures. In the transportation or handling of cream and milk-cans there has hitherto been considerable loss when cans have accidentally been overturned or dropped and the covers come out, but this is eliminated in the use of our device.

We claim:

1. In a container cover of the class described and having a flared circular opening and a lower integral closed cylindrical part adapted to close like parts of a container opening; a hand hold fixed diametrically in said cover and comprising a tubular member, a rotatable vertical pin mounted in said handle and projecting above it, and means on said pin on its projecting part to rotate said pin, a horizontally directed bearing in the cover at each end of said handle and the container provided with registering apertures exteriorly thereof, expanding rod means in said bearing parts and means within the handle on said pin for projecting said reciprocating rod means to simultaneously engage or be disengaged from said apertures of the container, said latter means comprising a pair of eccentric cams fixed on said pin, an eccentric strap engaging each cam, a bar extension on each strap and slidably engaged one in each of said bearing parts, said eccentric cams fixed on the pin so as to cause said rods to be expanded into the apertures of the container simultaneously or retracted therefrom as described.

2. The structure specified in claim 1 in which said pin and cam rotating means comprising a lever fixed on the said projecting part of the pin and operable in a horizontal plane and normally held frictionally on top of the said hand hold and longitudinally thereof when the locking rods are expanded.

In testimony whereof we affix our signatures.

WILLIAM WINGARD.
LEONARD VERHULST.
